DESIGN FOR A HOSE NOZZLE

Colin D. Barrett, deceased, late of Watertown, Conn., by Richard A. Barrett, executor, Watertown, Conn., assignor to Scovill Manufacturing Company, Waterbury, Conn., a corporation of Connecticut

Application September 17, 1937, Serial No. 71,664

Term of patent 14 years

To all whom it may concern:

Be it known that I, Richard A. Barrett, a citizen of the United States, residing at Watertown, county of Litchfield, State of Connecticut, am the executor of the last will and testament of Colin D. Barrett, late a citizen of the United States and resident of Watertown, in said county and State, who has invented a new, original, and ornamental Design for a Hose Nozzle, of which the following is a specification, reference being had to the accompanying drawing, forming part thereof, and in which,—

What is claimed is:

The ornamental design for a hose nozzle substantially as shown.

RICHARD A. BARRETT,
Executor of the Last Will and Testament of Colin D. Barrett, Deceased.
